SIGNORS OF ONE-THIRD TO E. P. PEERS AND ONE-THIRD TO GEORGE B. WINFREY,
BOTH OF LOS ANGELES, CALIFORNIA.

AUTOMATON ADVERTISING DEVICE.

Application filed May 3, 1926. Serial No. 106,390.

Our invention relates to an automaton that is especially designed for use in advertising cigars, cigarettes, and the like, the principal objects of our invention being to 5
5 provide a housing shaped to represent the head and shoulders of a person having a 10 cigar or cigarette holder in the mouth, to arrange on the interior of the housing a bellows and bellows actuating means, which 15 actuating means includes a small electric motor, and to provide connections between said bellows and apertures that are formed in the nose and mouth portions of the figure, whereby smoke from a lighted cigar or 20 cigarette positioned in the holder will be drawn into the bellows on its suction stroke and forced outwardly through the openings in the nose and mouth portions of the figure in simulation of the act of smoking. 25 Further objects of our invention are to provide a smoking automaton that is relatively simple in construction and which may be advantageously employed as an advertising device for cigars, cigarettes, and like tobacco products.

With the foregoing and other objects in view, our invention consists in certain novel features of construction and arrangement of parts that will hereinafter be more fully described and claimed and illustrated in the accompanying drawing, in which—

Fig. 1 is a front elevational view of a smoking automaton of our improved construction.

Fig. 2 is a rear elevational view of the device and showing the operating parts thereof.

Fig. 3 is a vertical section taken on the line 3—3 of Fig. 2.

Fig. 4 is an enlarged vertical section taken on the line 4—4 of Fig. 3.

Fig. 5 is an enlarged vertical section taken on the line 5—5 of Fig. 2.

Fig. 6 is an enlarged vertical section taken on the line 6—6 of Fig. 2.

Referring by numerals to the accompanying drawing which illustrates a practical embodiment of our invention, 10 designates a housing that may be formed of metal, 50 papier-mâché, compressed fiber, or other similar material, and which housing is shaped so as to represent the head and shoulders of a person.

Arranged in the upper rear portion of

this housing is a block 11 from one end of 55 which depends a bracket 12 and supported thereby is a small electric motor 13. One end of the shaft of this motor is extended, and carried by said extended end is a worm 14 that meshes with the teeth of a worm 60 wheel 15, the latter being fixed on one end of a shaft 16 that has bearing in a bracket 17. This bearing depends from the block 11 and mounted on the front end of the shaft 16 is a pinion 18 that is engaged by 65 the teeth of a gear wheel 19. This gear wheel is mounted on a stud 20 that is seated in the lower end of bracket 17 and projecting outwardly from the face of the gear wheel is a wrist pin 21.

Journalized on the wrist pin 21 is the upper end of a short rod 22, the lower portion of which is threaded and screw-seated in the upper portion of a tube 23. Screw-seated in the lower portion of this tube is the 75 threaded upper end of a rod 24, the lower end thereof being pivotally connected to the lower portion of a bellows 25, which latter is suitably supported in the lower portion 80 of the chamber within housing 10.

The threaded engagement of the rods 22 and 24 with tube 23 permits the connection between the wrist pin 21 and the bellows to be adjusted in length and after being properly adjusted, the rods 22 and 24 may be 85 locked to tube 23 by set screws 26 that are seated in said tube 23.

A block 27 is connected by a hinge 28 to the top of bellows 25, said block having a vertically disposed chamber 29 in which is 90 arranged for reciprocating movement a plate 30. Formed integral with the upper end of this plate is an outwardly projecting finger 31 that is notched or perforated for the accommodation of rod 24 and adjustably seated on said rod above and below the finger 31 are collars 32.

Formed through the central portion of plate 30 is a port 33 and one end of said port communicates with a vertically disposed slot 34 that is formed in the rear face of said plate. Formed through the rear portion of the block 27 is a port 35 that is always in communication with the slot 34, and leading from port 35 to the interior of 100 the bellows 25 is a flexible tube 36. Formed through the front wall of block 27 and arranged one immediately above the other are 105

ports 37 and 38 with which port 33 is adapted to alternately register as plate 30 is vertically reciprocated.

Passing through the wall of housing 10 and located on that portion of the housing that represents the mouth of the figure, is a short tubular member 39 with the forward end of which is formed integral a tapered tubular member 40 that serves as a cigar holder, and leading from port 37 to the inner end of the tubular member 39 is a small flexible tube 41.

Formed through the housing 10 to one side of the tubular member 39 and on that portion of the housing that represents the mouth of the figure is a small aperture 42, and formed through that portion of the housing that represents the nose of the figure are one or more apertures such as 43.

Connected to the inner ends of the apertures 42 and 43 are the upper ends of small metal tubes 44, the lower portions thereof being united and leading from the united ends of these tubes to port 38 is a flexible tube 45. Removably seated in the cigar holder 40 is a short tubular member 46 that is adapted to serve as a cigarette holder.

In the operation of our improved smoking automaton, a lighted cigar is placed in holder 40, or the holder 46 carrying a lighted cigarette is placed in said holder 40, and when the current is turned on to motor 13, the rotation of worm 14 drives worm wheel 15 and through pinion 18 the gear wheel 19 is driven. Owing to the relative sizes of worm 14, worm wheel 15, pinion 18 and gear wheel 19, the rotary motion of said gear wheel will be relatively slow, and as said gear wheel operates, the bellows will be slowly expanded and collapsed through the reciprocating action of the connections 22, 23 and 24.

While the reciprocating connection between the gear wheel 19 and bellows 25 is at the upper end of its stroke with the bellows fully collapsed, the engagement of the lower one of collars 32 against the underside of finger 31 positions plate 30 so that port 33 and slot 34 establish communication between ports 38 and 35, and during the first part of the downward travel of the connections between the gear wheel and bellows, plate 30 will remain stationary owing to the fact that the collars 32 are spaced apart and the lower one of said collars moves away from finger 31 before the upper collar engages with said finger to move the same and plate 30 downward.

Thus, while plate 30 is stationary and the bellows is being expanded, suction will be produced in tube 36, port 35, slot 34, ports 32 and 38, flexible tube 41, tubular member 39 and the cigar or cigarette holder, thereby drawing smoke from the lighted cigar or cigarette mounted in said holder and which

smoke will be drawn through the connections just mentioned into the bellows.

During the latter portion of the downward travel of the reciprocating connections between gear wheel 19 and the bellows, the upper one of collars 32 will bear on finger 31 to move plate 30 downward, thereby cutting off communication between ports 33 and 38 and establishing communication between ports 35 and 37. During the first portion of the succeeding upward stroke of the connection between gear wheel 19 and the bellows, the smoke previously drawn into the bellows will be expelled through tubular connection 36, port 35, slot 34, ports 33 and 37, flexible tube 45 and through the branches of tube 44 to the openings 42 and 43, and thus the smoke will be expelled or discharged from the nose and mouth portions of the automaton in simulation of the act of smoking.

Thus it will be seen that we have provided an automaton smoking device that is relatively simple in construction and which may be advantageously employed in show windows and the like, for advertising cigars or cigarettes.

It will be understood that minor changes in the size, form and construction of the various parts of our improved smoking automaton may be made and substituted for those herein shown and described without departing from the spirit of our invention, the scope of which is set forth in the appended claims.

We claim as our invention:

1. An automaton advertising device comprising a housing shaped to represent a person's head, a holder for a cigar or cigarette seated in the mouth representing portion of the head, there being smoke outlet openings formed through the mouth and nose representing portions of the head, a bellows arranged for operation within the housing, a valve housing arranged within the housing, a duct leading from the bellows to said valve housing, ducts leading from said valve housing to the cigar or cigarette holder and to the smoke discharge openings in the housing, a ported member arranged for sliding movement in the valve housing for establishing communication between the duct that leads from the bellows and the ducts that lead to the cigar or cigarette holder and to the smoke discharge opening and means within said housing for operating said bellows and the ported member within said valve housing.

2. An automaton advertising device comprising a housing shaped to represent a person's head, a holder for a cigar or cigarette seated in the mouth representing portion of the head, there being smoke outlet openings formed through the mouth and nose representing portions of the head, a bellows ar-

ranged for operation within the housing, a valve housing arranged within the housing, a duct leading from the bellows to said valve housing, ducts leading from said valve housing to the cigar or cigarette holder and to the smoke discharge openings in the housing, a ported member arranged for sliding movement in the valve housing for establishing communication between the duct 10 that leads from the bellows and the ducts that lead to the cigar or cigarette holder and to the smoke discharge opening, an electric motor arranged for operation in the upper portion of said housing, a train of 15 gearing arranged for operation within the housing and operated from said electric motor and operating connections from one of the members of said train of gearing to said bellows and the ported member within said 20 valve housing.

3. In an automaton advertising device, a housing shaped to represent a person's head, there being smoke outlet openings formed in the nose and mouth representing portions 25 of said head, a holder for a cigar or cigar-

ette seated in the mouth representing portion of said head, a bellows mounted for operation within the housing, a valve positioned on said bellows, a duct leading from said valve to the interior of the bellows, 30 ducts leading from said valve to said holder and to said discharge openings, a ported member arranged for sliding movement within the valve for establishing communication between the duct leading from the bellows to the valve and the ducts leading from said valve to the holder and discharge 35 openings, a motor driven train of gearing arranged for operation in the upper portion of the housing, a reciprocating connection between one of the members of the train of gearing and said bellows and means carried by said reciprocating member for shifting the position of the ported member 40 of said valve. 45

In testimony whereof we affix our signatures.

SANFORD W. CARTER.
